UNITED STATES PATENT OFFICE

90,617

DESIGN FOR A GRAVE MARKER

John A. Fumarol, Omaha, Nebr.

Application January 27, 1933. Serial No. 47,007

Term of patent 3½ years

To all whom it may concern:

Be it known that I, JOHN A. FUMAROL, a citizen of the United States, residing at Omaha, in the county of Douglas and State of Nebraska, have invented a new, original, and ornamental Design for a Grave Marker, of which the following is a specification, reference being had to the accompanying drawing, forming part thereof.

Figure 1 is a top plan view of a grave marker, showing my new design.

Figure 2 is a view in front elevation thereof.

Figure 3 is a side elevational view.

I claim:

The ornamental design for a grave marker as shown.

JOHN A. FUMAROL.
